[57] **CLAIM**

The ornamental design for a electromotion radio-control
light plane toy, as shown and described.

DESCRIPTION

FIG. 1 is a perspective view of a electromotion radio-control
light plane toy, showing our new design;
FIG. 2 is a front elevational view thereof;
FIG. 3 is a rear elevational view thereof;
FIG. 4 is a top plan view thereof;
FIG. 5 is a left side elevational view thereof;
FIG. 6 is a right side elevational view thereof;
FIG. 7 is a bottom view thereof; and,
FIG. 8 is a reference view showing a condition of removing
main wing and folding up propeller.
